UNITED STATES PATENT OFFICE.

JOHN N. CUNNINGHAM, OF ALLEGHENY, PENNSYLVANIA.

ATTACHMENT FOR OVAL OR SQUARE MAT CUTTING MACHINES.

SPECIFICATION forming part of Letters Patent No. 671,208, dated April 2, 1901.

Application filed January 31, 1901. Serial No. 45,491. (No model.)

To all whom it may concern:

Be it known that I, JOHN N. CUNNINGHAM, a citizen of the United States of America, residing at Allegheny, in the county of Allegheny and State of Pennsylvania, have invented certain new and useful Improvements in Attachments for Oval or Square Mat Cutting Machines, of which the following is a specification, reference being had therein to the accompanying drawings.

This invention relates to certain new and useful improvements in oval-cutting machines, and more particularly to that class of machines to form mats for frames or the like.

15 The invention has for one object to construct a device of the above-described character that will effectually retain a large number of layers of matting or other suitable material employed for the above-mentioned purpose.

20 Another object of the present invention is to construct a mechanism that will firmly retain and clamp in an effectual manner a number of layers of cardboard or the like and will permit a cutter to cut through several thicknesses in one operation.

25 Another object of this invention is to construct a machine of the above-described character wherein the mats may be easily released, and, furthermore, wherein the oval cut from the mat may be readily removed.

30 With the above and other objects in view the invention consists in the novel combination and arrangement of parts, to be hereinbelow more fully described, and specifically pointed out in the claims.

35 In describing the invention in detail reference is had to the accompanying drawings, forming a part of this specification, and wherefore like numerals of reference indicate corresponding parts throughout the several views, in which—

40 Figure 1 is a side elevation of my improved oval-cutting machine. Fig. 2 is a front view thereof. Fig. 3 is a perspective view of the yoke and foot-lever.

45 In the drawings the reference-numeral 1 indicates the base or frame of the machine, having upright standards 2 and 3, and a table or base-board 4, mounted upon said standards. The said table is provided with suitable openings to receive the upwardly-ex-

tending arms 5 of the yoke 6, said upwardly-extending arms extending through said openings. The said yoke 6 is provided with a 55 downward extension 7, having a bifurcated end 8, to which is pivotally secured a foot-lever 9, said foot-lever 9 being pivotally connected at its end, as shown at 10, to a lug 11, arranged to the cross-bar 12 of the frame. 60 The said yoke 6 is also provided with an apertured boss 14, through which extends the rod 15, connected at 16 to the under face of the table 4, the lower end of said rod being attached at 17 to a coil-spring 18, connected 65 at 19 to the foot-lever 9.

The reference-numeral 20 represents a yoke having a round or oval central portion 21, this yoke being pivotally secured at 22 23 to the upper extremity of the upwardly-extending arms 5.

The reference-numeral 24 represents a toothed rack which is suitably secured to the connecting-piece 25 of the standards 3, the latter being adapted to engage the foot-lever 75 9 and retain the same in position.

The reference-numeral 26 represents apertured lugs arranged at each side at the rear portion of the table to receive the frame 27 of the cutter, said cutter being provided with 80 a downwardly-extending curved arm 28, said arm being engaged by the end 29 of the lever 30, which is fulcrumed at 31 to the side of the table, the forward end of said lever 30 carrying a handle 32. This lever has an inwardly-projecting portion 33, which is adapted to engage the toothed rack 34 and retain the cutting-frame in an elevated position when desired.

The reference-numeral 35 represents a cutter arranged to the forward end of the cutting-frame, the latter being operated in the usual manner.

90 The operation of my improved oval-cutting machine is as follows: A number of layers of mats that are to be cut are placed upon the table under the yoke 20, foot-pressure applied to the foot-lever, and the same locked in the toothed rack. The lever 30 is then raised, thereby lowering the cutting-frame and also 95 the cutter. The operation is then performed in the well-known manner, the cutter penetrating through a number of layers in one operation, and the ovals produced by this op-

eration can then be readily removed by the use of a knife or any sharp instrument through the round or oval portion of the yoke.

The many advantages obtained by the use of my improved device will be readily apparent from the foregoing description, as it has been heretofore a difficulty to obtain a firm grasp upon a number of layers.

It will be noted that in case square mats are to be cut in lieu of the oval yoke square clamps may be employed that will firmly engage the upper face and sides of the mats and retain the same in the proper position. Further, it will be noted that various changes may be made in the details of construction without departing from the general spirit of my invention.

Having thus fully described my invention, what I claim as new, and desire to secure by Letters Patent, is—

1. In an oval-cutting machine, the combination of a suitable frame and table mounted thereon, upwardly-extending arms extending through said table, a yoke secured to said arms, a foot-lever connected to said arms, a cutter-frame, means to raise and lower said cutter-frame, and a cutter arranged upon said cutter-frame.

2. In an oval-cutting machine, the combination of a suitable frame carrying a table

having openings therein, upwardly-extending arms arranged in said openings, a downwardly-extending portion connecting said arms, a foot-lever secured to the lower extremity of said downwardly-extending portion and pivotally connected thereto, said foot-lever being pivotally secured to the cross-piece of the frame, a rod secured to the under face of said table, an apertured boss secured to the yoke, said rod extending through said boss, a spring connecting said rod and foot-lever, a cutter-frame pivotally secured to the rear end of said table, a downwardly-extending arm arranged and carried by said cutter-frame, an operating-lever adapted to raise and lower said cutter-frame and operate against the lower face of said curved arm, a yoke pivotally secured to the upper extremity of said arms, and a cutter rotatably secured in said cutter-frame and operating in said yoke, all parts being arranged and operating substantially as herein shown and described.

In testimony whereof I affix my signature in the presence of two witnesses.

JOHN N. CUNNINGHAM.
